LEO GINSBURG, OF CHICAGO, ILLINOIS

HYDROTHERAPEUTIC APPARATUS

Application filed June 7, 1930. Serial No. 459,722.

This invention has to do with hydrotherapy, which is the treatment of certain diseases, disorders and ailments by the external application of water and other liquids.

One of the principal objects of the invention is to provide a novel apparatus for use in administering a hydrotherapeutic massage by intermittent or spasmodic jet impact.

Other objects and advantages of the invention will be apparent to those skilled in the art upon a full understanding of the method and the apparatus used in practicing the same.

One form of the invention is presented herein for the purpose of exemplification, but it will of course be appreciated that the invention is susceptible of embodiment in other forms coming equally within the scope of the appended claims.

In the accompanying drawing:

Fig. 1 is a vertical section through a massage machine constructed in accordance with the invention;

Fig. 2 is another vertical section through the machine, taken on the line 2—2 of Fig. 1;

Fig. 3 is a horizontal section through the head of the machine, taken on the line 3—3 of Fig. 2;

Fig. 4 is a vertical section through the cylinder on the front end of the head, taken on the line 4—4 of Fig. 1; and

Fig. 5 is a fragmentary vertical section through the front end of the cylinder, corresponding to a portion of Fig. 1, showing a curved jet plate substituted for the straight one.

The machine shown in the drawing includes a pedestal 10 which is mounted on caster wheels 11 for movement from place to place. The pedestal carries a head 12 which is both vertically and angularly adjustable and is provided with a cylinder 13. The cylinder is closed at its rear end by a solid plate 14 and is closed at its front end by a perforated plate 15 which is detachably held in position by means of a screw-threaded clamping ring 16.

A piston rod 17 extends into the cylinder 13 through a packing gland 18 in the rear plate 14 and carries a piston 19 which slid-

ably fits within the cylinder. The piston is rigidly attached to the rod near the front end of the latter and is peripherally sealed against leakage by means of two piston rings 20. A flat valve plate 21 is shiftably mounted on the front end of the rod between the piston and a forwardly spaced retaining nut 22 and is splined thereon to prevent turning. The piston is provided with a number of circumferentially spaced sector-shaped openings 23, and the valve plate, which is slightly smaller in diameter than the piston, is provided with a corresponding number of circumferentially spaced sector-shaped ears 24 which are slightly larger in size than the openings 23 and are adapted to close off such openings when the valve plate is shifted into a position against the piston. The front face of the valve plate is preferably reinforced by an integrally formed annular rib 25.

The water which is acted upon by the machine flows into the cylinder 13 through a port 26 in the rear plate 14. The port 26 is adapted to be connected by a flexible hose to a water faucet or other convenient supply of water under pressure. In operation, the piston 19 is reciprocated rapidly back and forth in the cylinder, and the valve plate 21, which moves back and forth with the piston 19, changes its position with respect to the piston at each stroke. As the piston moves forwardly, the valve plate settles back against the front face of the piston and closes off the openings 23 therein, and, as the piston moves rearwardly, the valve plate draws away from the piston and uncovers the openings. As a result, the water which is constantly flowing into the cylinder through the port 26 passes forwardly through the openings 23 in the piston on the rearward stroke of the latter and is trapped in front of the valve plate on the next forward movement of the piston and forcibly ejected through the openings in the jet plate 15. The piston and the piston plate, in cooperation with the jet plate, cause the water to be shot from the front end of the cylinder intermittently or spasmodically in surges of fine sharp spray. The impact of this spray against the surface being treated is

pulsating and vibratory in character and is not unlike an ordinary massage in some of its effects, although far superior to the latter from a medical standpoint.

The rear end of the piston rod 17 is rigidly connected to a block 27 which is slidably supported in spaced ways 28, and the block is in turn pivotally connected at 29 to a rearwardly extending and laterally offset arm 30 which carries a circular strap 31. The strap 31 is rotatably mounted on an eccentric 32 which is attached to a cross shaft 33. The ends of the shaft 33 are journaled in bearings 34 in the sides of a casing 35 which forms the rear portion of the head 12. The shaft 33 is rotated by a beveled gear 36 which is attached to the same and meshes with another beveled gear 37 on the upper end of an upright shaft 38. A gear 39 is splined to the shaft 38 between two arms 40 of a bearing bracket 41 and meshes with a small pinion 42 which is secured to the upper end of a countershaft 43. A gear 44 is attached to the lower end of the countershaft 43 and meshes with a small pinion 45 which is mounted directly on the armature shaft of a variable speed electric motor 46. From the foregoing, it will be understood that the motor 46 rotates the cross-shaft 33 through the double reduction provided by the gears 45, 44, 42 and 39.

The head 12 of the machine is tiltably supported in a U-shaped yoke 47 which is formed on the upper end of an upright tubular post 48, the upper ends of the sides of the yoke 47 being apertured to receive trunnions 49 which are formed on the sides of the casing 35 in concentric relation to the ends of the cross-shaft 33. The shaft 38 is arranged centrally within the post 48. By reason of this construction, the head 12 may be tilted into different angular positions without disturbing the driving relation between the shafts 33 and 38. The head 12 may be held in any position of angular adjustment by means of a serrated cam 50 which is pivotally attached to one of the sides of the yoke 47 at 51 and is provided with a handle 52 by means of which the serrated portion of the cam may be wedged into engagement with a projecting portion of one of the trunnions 49. The rear end of the casing 35 is preferably weighted in order to partially counterbalance the cylinder 13.

The head 12 may also be bodily raised or lowered into any desired position. The tubular post 48 which carries the head is vertically shiftable in a collar 53 which is formed on the upper end of the pedestal 10. The collar 53 has associated therewith a serrated cam 54 which is similar to the cam 50, and, when the cam 54, which is pivoted to the collar at 55 and is operated by a handle 56, is turned in one direction, it will grip the post 48 through a slot 57 in the collar and will hold

the post in any desired position of vertical adjustment.

The shape and character of the spray produced by the machine may be varied by changing the shape of the front plate 15 and also by changing the arrangement of the perforations in that plate. In order to obtain a rather widely diffused spray, a curved plate 58 such as shown in Fig. 5 may be substituted for the straight plate 15. Many different effects can also be produced by changing the size of the perforations in the plate.

The frequency of the impacts may be increased or decreased by speeding up or slowing down the motor, through a suitable manually-operated rheostat, while the sharpness of the impacts can be increased or decreased by regulating the rate of flow of water into the cylinder through the port 26.

I claim:

1. Hydrotherapeutic apparatus, comprising a cylinder, a perforated plate at the front end of the cylinder, a solid plate at the rear end of the cylinder, an inlet port in the rear plate, a piston rod extending through the rear plate into the cylinder, a piston rigidly attached to the rod, a valve plate slidably mounted on the rod in front of the piston for limited movement toward and away from the latter, and means for rapidly reciprocating the rod in the cylinder, said piston being provided with a number of circumferentially spaced sector-shaped openings, and said valve plate being provided with a corresponding number of circumferentially spaced sector-shaped portions which are adapted to cover the openings in the piston when the latter is moved forwardly in the cylinder by the rod.

2. In an apparatus of the character described, a cylinder, a perforated plate at the front end of the cylinder, a piston in the cylinder, a valve on the piston and positioned between the latter and said plate and which opens when the piston is moved rearwardly and closes when the piston is moved forwardly, a water inlet in the cylinder behind the piston, an electric motor, and a power-transmitting connection between the motor and the piston for rapidly reciprocating the latter in the cylinder, whereby to cause the water entering the cylinder to be ejected spasmodically therefrom in a fine forcibly surging spray.

3. Hydrotherapeutic apparatus, including a support, an angularly adjustable head pivotally mounted in proximity to its rear end on said support, a nozzle element fixed to the forward end of said head and bodily movable with the latter, reciprocatory means within the nozzle element for forcibly ejecting water from the latter in a pulsating spray, an electric motor mounted on the support and connected flexibly with said means for rapidly operating the same, and readily

- releasable means for securing the head rigidly with respect to the support in any one of several angularly disposed positions.
4. In a hydrotherapeutic apparatus, a tubular nozzle element having a foraminous forward end and a closed rear end, formed with an axial opening and an opening adjacent the latter, means communicating with said adjacent opening for supplying water to said element at the rear thereof, a reciprocatory element including an apertured valve controlled piston operating in said nozzle element and further including a piston rod extending rearwardly through said axial opening, and motor driven means for rapidly reciprocating said reciprocatory element to produce a periodically interrupted impact jet of water having a vibratory effect upon the surface against which directed.
5. In a hydrotherapeutic apparatus, a tubular nozzle element having a foraminous forward end and a closed rear end, formed with an axial opening and an opening adjacent the latter, means communicating with said adjacent opening for supplying water to said element at the rear thereof, a reciprocatory element including an apertured valve controlled piston operating in said nozzle element and further including a piston rod extending rearwardly through said axial opening, motor driven means for rapidly reciprocating said reciprocatory element to produce a periodically interrupted impact jet of water having a vibratory effect upon the surface against which directed, a pedestal, a support extended from the pedestal, a hollow head closed at one end and open at its other end, means for coupling the rear end of the nozzle element in the open end of said head, said head, support and pedestal enclosing said motor driven means, said support being vertically adjustable, and said support and pedestal having coacting means for releasably holding the support in its adjusted position.
6. In a hydrotherapeutic apparatus, a tubular nozzle element having a foraminous forward end and a closed rear end, formed with an axial opening and an opening adjacent the latter, means communicating with said adjacent opening for supplying water to said element at the rear thereof, a reciprocatory element including an apertured valve controlled piston operating in said nozzle element and further including a piston rod extending rearwardly through said axial opening, motor driven means for rapidly reciprocating said reciprocatory element to produce a periodically interrupted impact jet of water having a vibratory effect upon the surface against which directed, a pedestal, a support extended from the pedestal, a hollow head closed at one end and open at its other end, and means for coupling the rear end of the nozzle element in the open end of said head, said head, support and pedestal enclosing said motor driven means.
7. In a hydrotherapeutic apparatus, a tubular nozzle element having a foraminous forward end and a closed rear end, formed with an axial opening and an opening adjacent the latter, means communicating with said adjacent opening for supplying water to said element at the rear thereof, a reciprocatory element including an apertured valve controlled piston operating in said nozzle element and further including a piston rod extending rearwardly through said axial opening, motor driven means for rapidly reciprocating said reciprocatory element to produce a periodically interrupted impact jet of water having a vibratory effect upon the surface against which directed, a pedestal, a support extended from the pedestal, a hollow head closed at one end and open at its other end, means for coupling the rear end of the nozzle element in the open end of said head, said head, support and pedestal enclosing said motor driven means, said support being vertically adjustable, and said support and pedestal having coacting means for releasably holding the support in its adjusted position.
8. In a hydrotherapeutic apparatus, a tubular nozzle element having a foraminous forward end and a closed rear end, formed with an axial opening and an opening adjacent the latter, means communicating with said adjacent opening for supplying water to said element at the rear thereof, a reciprocatory element including an apertured valve controlled piston operating in said nozzle element and further including a piston rod extending rearwardly through said axial opening, motor driven means for rapidly reciprocating said reciprocatory element to produce a periodically interrupted impact jet of water having a vibratory effect upon the surface against which directed, a pedestal, a support extended from the pedestal, a hollow head closed at one end and open at its other end, means for coupling the rear end of the nozzle element in the open end of said head, said head, support and pedestal enclosing said motor driven means, said head being angularly adjustable, said head and support having coacting means for releasably holding the head in its adjusted position, said support being vertically adjustable, and said support and pedestal having coacting means for releasably holding the support in its adjusted position.
9. In testimony whereof I have hereunto subscribed my name.

LEO GINSBURG.
